SHOE SOLE CONSTRUCTION

Samuel L. Kleven, Augusta, Maine

Application May 12, 1943, Serial No. 486,651

2 Claims. (Cl. 36—31)

This invention relates to outsoles particularly well adapted for play shoes or the like.

Under present conditions which make necessary the conservation of leather, the need for an outsole structure requiring a minimum of leather and combining good wearing qualities and attractive appearance with economy in manufacture, is well recognized. Various attempts have been made to provide substitutes for conventional leather outsoles, but these have not proved acceptable.

In accordance with my invention, I provide an outsole consisting of a fabric body such as a blank of belting impregnated with a waterproof cement to which is stitched an edging strip or trim, preferably of leather, but which may be completed by a thermo-plastic heel portion stitched to the blank. The upper surface of the outsole is marginally coated with a waterproof cement with the coat extending inwardly to cover the margin of the blank. The bottom surface of the insole structure is coated with such cement so that when the outsole is to be attached, it is only necessary to apply a solvent to one of the coated surfaces and then press the outsole and the shoe together until the cement has set to bond the outsole as a unit to the shoe.

By this construction, I am able to provide outsoles at a low cost which require a minimum of leather, have good wearing qualities, and are of attractive appearance. In the accompanying drawing, I have shown my invention as embodied in footwear of the play shoe type as such footwear well illustrates these and other novel features and advantages of my invention.

Fig. 1 is a bottom perspective view of a shoe in accordance with my invention.

Fig. 2 is a bottom plan view of a shoe to which the sole is to be attached.

Fig. 3 is a top plan view of the sole; and

Fig. 4 shows a transverse section through a shoe severed adjacent the ball of the foot.

In Fig. 1, I have shown a shoe consisting of an upper 5 having an insole 6, a platform 6^a stitched thereto as at 6^b, and a lift 7 of the wedge type and defining with the platform 6^a forwardly thereof the surface (see Fig. 2) to which the outsole, generally indicated at 8, is attached.

The construction of the outsole 8 may be best understood by reference to Fig. 3 in which I have shown a fabric body or blank 9 substantially in the shape of the sole and impregnated with a waterproof cement, such as pyroxolin cement. Cotton woven belting of 4 or 4½ inches is well adapted for such a blank.

To the edge of the blank 9, I stitch as by the zig-zag stitching S a trim 10 of the same thickness as the blank 9. Preferably the trim is of leather and preferably it is in the form of a strip 5 which may be shaped to the blank 9 as it is stitched thereto. The trim 10 provides a reinforcing margin that not only eliminates fraying of the fabric at its edges as the shoe wears, but also provides a clean, neat edge capable of taking a high polish and gives the sole, in side view, the appearance of an all leather sole.

In the drawing I have shown, in the heel area, a heel portion 11 stitched to the blank 9. The heel portion 11 is cut or molded to the correct 15 size from a thermoplastic such as "Vinylite" and is of the same thickness as the blank 9 so that a neat joint is established. Heel portion 11 is cross-stitched to blank 9 as by the zig-zag stitching S so that blank 9, trim 10, and heel portion 20 11 may be handled as a unit.

The upper surfaces of the trim 10 and heel portion 11 and the margin of the blank 9 are coated with pyroxolin cement as at 12. Conveniently, the coat 12 may extend about a quarter 25 of an inch inwardly from the edge of the blank 9. The sole receiving surface of the shoe is provided with a coat, indicated at 13, of pyroxolin cement as shown in Fig. 2, so that the outsole may be quickly and easily attached by applying a solvent to either of the coats 12, 13 and pressing the coated surfaces together until the cement has set to provide an effective bond indicated at 14 in Fig. 4.

In accordance with my invention, I am thus 35 able to provide an inexpensive sole of attractive appearance that may be quickly and easily attached to the shoe. The impregnated blank 9 has good wearing qualities and is acceptably waterproof and the trim 10 serves both to give the sole an attractive appearance and to provide reinforcement.

What I therefore claim and desire to secure by Letters Patent is:

1. An outsole having a fore part and a heel part, said fore part comprising a sole blank impregnated throughout substantially its entire area with a waterproofing substance, and a trim of substantially the same thickness as said blank fastened to and extending marginally around said blank back to said heel part and of a width to constitute a substantial portion of the tread surface of the fore part, and said heel part comprising a heel blank abutting the ends of the trim and the rear edge of said sole blank and of substantially the same thickness as said sole blank

and trim, and cross-fastenings connecting said fore and heel parts.

2. An outsole having a fore part and a heel part, said fore part comprising a sole blank of woven cotton belting impregnated throughout substantially its entire area with a waterproofing cement and a trim of substantially the same thickness as said blank fastened to and extending marginally around said blank back to said heel part and of a width to constitute a substantial portion of the tread surface of said fore part, said heel part comprising a heel blank

abutting the ends of the trim and the rear edge of said sole blank and of substantially the same thickness as said sole blank and trim, means connecting said fore and heel parts, and a coating of waterproofing cement applied to the upper surface of said trim and to the upper surface of said sole blank inwardly of said trim to provide with the cement with which the sole blank is impregnated a bonding medium whereby the outsole may be attached to a shoe.
